MERCURY SWITCH RELAY

Carl H. Larson, Elkhart, Ind., assignor to The
Adlake Company, a corporation of Illinois

Application March 24, 1936, Serial No. 70,602

6 Claims. (Cl. 200—112)

In electro-mechanical relays, it is common practice, and in fact absolutely necessary, to provide some means for establishing the proper air gap when the relay is energized, for otherwise the remanence in the iron circuit of the relay would cause relay failure. Ordinarily, a set screw of non-magnetic material is used to prevent the armature of electro-mechanical relays from making physical contact with the rest of the iron circuit, the set screw being adjusted so that the total reluctance of the entire magnetic circuit is sufficiently high that when the relay coil is de-energized, the remanence in the iron circuit does not affect the opening of the relay.

In mercury switch relays of the type described in the Larson Patent 1,967,247, the problem is less difficult, because the thickness of the glass is in itself an air gap. However, in some mercury switches, where certainty of operation is of the utmost importance, it is desirable to provide other safeguards against relay failure, due to remanence in the iron circuit. The principal object of this invention is to provide such other safeguards.

Further and other objects and advantages of this invention will become apparent as the disclosure proceeds and the description is read in conjunction with the accompanying drawings, in which

Fig. 1 is a diagrammatic view of a flasher made in accordance with this invention, the switch parts being shown in the position they assume just prior to the energization;

Fig. 2 is a perspective view of the control switch displacer;

Fig. 3 is a view similar to Fig. 1, but the switch parts are shown in the position they assume just prior to de-energization of the control switch;

Fig. 4 is a diagrammatic view of a portion of the magnetic circuit, with a portion of the lower pole piece counterbored;

Fig. 5 shows a front contact switch associated with a magnetic circuit constructed in accordance with this invention;

Fig. 6 is a fragmentary view of a switch associated with a magnetic circuit in which both pole pieces are counterbored;

Fig. 7 is a rear perspective view showing the physical form of the flasher relay;

Fig. 8 is a vertical, sectional view taken on the line 8—8 of Fig. 7.

It will be understood that the embodiments of the invention shown in the drawings and the specific description which follows are for the purpose of disclosure only and should not be construed as

imposing limitations on the appended claims except as may be required by the prior art.

THE CIRCUIT BREAKERS

1. Control switch

The control switch 32 (Fig. 1) is a back contact switch and comprises a switch envelope 40, preferably of glass, through the bottom of which spaced electrodes 41 and 42 are sealed. The central electrode 41 is surrounded by an insulating sleeve 43, preferably of glass, for a portion of its length, and the exposed end of the electrode is bent over with its end 44 alongside the insulating sleeve 43. This is done to prevent the arc of making and breaking the circuit from taking place at the end of the insulating sleeve 45, which would eventually result in disintegration of the sleeve.

The switch envelope contains a quantity of mercury 46 which is adapted under certain conditions to bridge the electrodes 41 and 42.

The displacer 47 by its position within the switch envelope determines the level of the mercury. It comprises (Figs. 1 and 2) a sleeve 48 of magnetic material telescoped over a glass tube 49 closed at upper end except for a small opening 50 and open at its lower end. The upper end of the glass tube is packed with cotton 51.

The control switch is, in this case, a self-acting intermittent circuit breaker in which the rate of gas flow through the cotton determines the time interval between the making and breaking of the electrical circuit through electrodes 41 and 42.

Guide washers 52 and 53 have three or more smoothly rounded lugs 54 and 55 lightly touching the walls of the switch envelope in the vertical movement of the displacer 47. The guide washers are held in place by springs 56 which also serve to protect the switch envelope from breakage during shipping, due to any motion of the displacer.

Before sealing off the switch envelope at 57, it is evacuated and all the metal parts are degassed. The switch is then filled with an inert gas (helium, hydrogen, helium hydride, or the like).

The displacer 47 of the control switch 32 is adapted to oscillate within the switch envelope at a predetermined rate of oscillation, and in Fig. 1 the parts are shown in the position which they assume just before the circuit through the electrodes 41 and 42 is closed. The mercury level on the outside of the displacer 47 is higher than the level on the inside of the displacer, this

difference of mercury levels being due to a slight gas pressure differential. This gas pressure differential is equalized by the outward flow of gas through the cotton packing 51, and thence 5 through the small opening 50 at the top of the displacer. This results in the rise of the mercury level within the displacer and the fall of the mercury level on the outside. When the mercury level inside rises sufficiently to contact 10 the end 44 of the electrode 41 the circuit through the switch is closed and the relay coils 71 become energized. The displacer is then lifted to the position shown in Fig. 3 and draws up with it a column of mercury as shown. This again 15 results in a gas pressure differential, between the gas on the inside of the displacer and that on the outside, but in this case the pressure is less on the inside of the displacer than on the outside, so that there results a flow of gas back 20 into the displacer through the opening 50 and cotton packing 51. As the gas pressure differential is equalized, the mercury level on the outside of the displacer rises and that on the inside falls until the mercury level falls below the 25 end 44 of the electrode 41. This breaks the circuit and the relay coils 71 become de-energized and the displacer falls by gravity to the position shown in Fig. 1.

In Fig. 3, the control switch 32 is shown in 30 the position just before the circuit between the spaced electrodes 41 and 42 is broken by the receding mercury column within the displacer.

The magnetic circuit generally designated 62 associated with switch 32 comprises the relay 33 coils 71 and iron circuit 72. The iron circuit is closed except for an air gap 73, the air gap formed by the thickness of the switch envelope and counterbore 74 in the lower pole piece. The air gap formed by the counterbore 74 is so arranged that the lower end 75 of the magnetic sleeve 48 of the displacer 47, in its downward movement, enters the counterbore 74 before the upper end 76 enters the air gap 73.

As a result, the danger of having the displacer 48 suspended in a position somewhat above the normal de-energized position, due to remanence in the iron circuit, is substantially eliminated.

2. Lamp circuit breaker

56 The lamp circuit breaker 33 (Fig. 1) is similar in many respects to the physical appearance of control circuit breaker 32, but it functions somewhat differently. The switch comprises a switch envelope 80, through the bottom of which spaced 55 electrodes 81 and 82 are sealed, a mercury fill 83 and a displacer 84.

The switch 33 is a fast acting back contact switch and the mercury fill 83 bridges the electrodes 81 and 82 when the relay coil 71 is de-energized and the displacer 84 is down under the action of gravity.

The displacer 84 comprises a magnetic sleeve 85 telescoped over an elongated glass thimble 86 having a small opening 87 in its top wall. 65 The glass thimble 86 and the magnetic sleeve 85 are held in proper relative position by springs 88, which also clamp the guide washers 89 and 90 to the sleeve 85.

In the de-energized position (Fig. 1), the displacer 84 floats on the mercury 83 raising the level to bridge the electrodes 81 and 82, completing the circuit to the signal lamp 100. When the relay coils 71 are energized, the displacer 84 is raised to the position shown in Fig. 3, 75 causing the mercury level to fall below the ex-

posed end 91 of electrode 81 and thus breaking the circuit to the signal lamp 100.

The magnetic circuit associated with the switch 33 comprises a continuation of the iron circuit 72 and relay coils 71. The iron circuit 5 is similar to that associated with switch 32 except that the air gap 92 is smaller, having been partly closed by the addition of the iron sleeve 79 which tends to lower the pick up value of the switch. Like the iron circuit associated with 10 switch 32, the lower pole piece is counterbored as indicated at 93. Again the counterboring is arranged so that the lower end 94 of the magnetic sleeve enters it before the upper end 95 enters the air gap 92. This counterboring 93 as 15 consists in overcoming the effect of remanence and substantially eliminates the possibility of switch failure due to residual magnetism.

Circuit breaker 34 normally functions as a front contact switch, but in case of relay failure, 20 it functions as a back contact switch. The switch is similar in many respects with switches 32 and 33 and in so far as the parts are alike, the same reference characters will be used. The switch comprises a switch envelope 80, spaced 25 electrodes 97 and 98, a mercury fill 83 and a displacer 96. The displacer thimble 86 is packed with cotton 99 to retard the movement of mercury within the displacer thimble.

When the coils 71 are energized, the displacer 30 96 is lifted completely out of the mercury, which allows any mercury within the thimble 86 to fall away from the displacer, and since the mercury fill in the envelope is sufficient to bridge the electrodes 97 and 98 when the displacer is raised 35 (Fig. 3) the circuit through lamp 101 is closed.

When the coils 71 are de-energized, the displacer falls to the position shown in Fig. 1, but before the time delay element 99 has permitted mercury to rise within the thimble a sufficient 40 amount to make contact with the tip 91 of the electrode 97, the coils 71 are again energized so that the displacer is lifted to the position shown in Fig. 3.

In case the power for the control circuit fails 45 for any reason, leaving the coils 71 de-energized, the front contact switch 34 acts as a back contact switch, for unless the coils 71 pick up the displacer 96 within a given period of time, the mercury rises sufficiently within the displacer to 50 bridge the contacts 97 and 98.

It will be noticed that in case of relay failure, both signal lamps 101 and 102 would be lighted and even if one signal lamp should be burned out there would be at least one signal lamp illuminated.

THE CIRCUITS

1. The control circuit

The control circuit is shown in light lines and 60 functions to intermittently energize the relay coils 71. In case the flasher is used at a railroad crossing, the local circuit is placed into operation whenever a train enters a given section of track and short circuits the track relay 110 65 which includes a back contact switch 111 associated with the control circuit and a back contact switch 112 associated with the lamp circuit. The control circuit in practice is ordinarily energized by a battery 113 and the control switch 32 and 70 the relay coils 71 are connected in series with the battery 113 and the back contact switch 111 of the track relay. The circuit can be traced from the battery 113 through the conductor 114, switch 111, conductor 115, electrode 41, mer- 75

cury 46, electrode 42, conductors 116 and 117, to the relay coils 71, and back to the battery through conductor 118.

This circuit makes the control switch 32 a self-acting intermittent circuit breaker, the rate of oscillation of which is determined by the rate of flow of gas through the time delay element 51.

2. Lamp circuit

10 The lamp circuit is shown in heavy lines and includes the lamp circuit breakers 33 and 34, lamps 100 and 101, the back contact switch 112 of the track relay 110 and the secondary coil 102 of the transformer 103 which in practice is ordinarily energized from a 110 volt alternating current line.

15 The lamp 100 is controlled by the circuit breaker 33 and the lamp 101 by the circuit breaker 34 and when the coils 71 are de-energized (as in Fig. 1) the circuit through the lamp 100 may be traced from the secondary coil 102 through the conductor 120, through the back contact switch 112, conductor 121, lamp 100, conductor 122, electrode 81, mercury 83, electrode 82, conductor 123, and through conductor 124 back to the secondary coil 102 of the transformer 103.

20 When the relay coils 71 are energized (as in Fig. 3), the circuit through the lamp 101 may be traced from the secondary coil 102 of the transformer 103 through the conductor 120, back contact switch 112, conductor 121, lamp 101, conductor 125, electrode 97, mercury 83, electrode 98, conductor 126 and back through conductor 124 to the secondary coil 102 of the transformer 35 103.

OPERATION

30 Switch 32 functions as a self-acting intermittent circuit breaker controlling the intermittent energization of the relay coils 71, which in turn 40 actuate the lamp circuit breakers 33 and 34, one of which functions as a back contact relay and the other as a front contact relay. As long as the coils 71 are intermittently energized above a predetermined frequency, the lamps 100 and 101 will be alternately lighted and the desired 45 flashing signal indication will be obtained.

50 In case of failure of the control circuit (shown in light lines), the relay coils 71 become permanently de-energized, in which case both switches 33 and 34 act as back contact switches and both lamps 100 and 101 would be lighted.

PHYSICAL FORM OF THE RELAY

55 The relay is mounted on an L-shaped bracket 130 (Figs. 7 and 8) for support, which carries a plurality of relay coils 71, the upper two being associated with a top pole piece 132, and the lower two being associated with a bottom pole piece 133. The relay coils 71 have iron cores 134, with external iron connectors 135 which are held in place against the coils 71 by the nuts 131 screwed to the threaded ends of the pole pieces 134. The pole pieces 132, 133, the iron cores 134 and external connectors 135 constitute the iron circuit 72.

60 The poles 132 and 133 have vertical aligned apertures 135, 136 and 137 adapted to receive the control circuit breaker 32 and lamp circuit breakers 33 and 34, respectively.

65 The switches 32, 33 and 34 are adjustably mounted within these apertures. In the pole pieces 132 and 133 vertically aligned holes 138 and 139 are drilled to hold adjusting rods 140. A 70 spring clip 142 (best shown in Fig. 8) is fastened

at one end around the base 143 of the mercury switch tube, and at the other end to the adjusting rod 140 by nuts 144 and 145 screwed to the end 146 of the rod. A spring 147 interposed between a wear washer 148 and the nut 144 tends to force the rod downwardly and this is resisted by the nuts 149 and 150 which are screwed on the threaded end 151. Cork washers 152 are provided between the lower nut 149 and the pole piece 132. This arrangement permits raising 10 and lowering of the switches to a desired position and locking into place.

COUNTERBORED POLE PIECES

(a) Lower pole piece

15

No attempt will be made to explain in detail the theory which is believed to account for the advantages achieved by counterboring, for at best, it would only be conjectural. Certain 20 advantages, however, are known to exist when one or more of the pole pieces are counterbored in accordance with this invention.

25 Counterboring of the lower piece is particularly advantageous when the iron circuit is associated with a pull-up switch, such for example as switches 32, 33, 34, of the flasher relay. The counterbore 74 associated with the control switch 32 has the desirable effect of limiting the height to which the displacer rises within the envelope 30 irrespective of the voltage applied to the coil 71; of shortening the travel of the displacer and making the stroke more uniform for relatively large variances in the voltage applied to the coils, thereby producing a more uniform rate of 35 flasher operation under the varying conditions of service; and of substantially limiting the possibility of switch failure due to remanence in the iron circuit by increasing the air gap at the lower pole piece when the effect of remanence 40 is greatest in the vicinity of the upper pole piece.

45 The counterboring 93 of the lower pole piece for the switches 33 and 34 has much the same effect as the counterboring 74 for the switch 32. The principal advantage of the counterboring, however, for the switches 33 and 34 is to overcome the effect of remanence in the iron circuit because the air gap 92 between the pole pieces is smaller than the air gap for the controlling switch 32. The position of the displacer 84 where the effect of remanence is greatest is shown in Fig. 4. Again, it will be observed that in this position, the lower portion of the displacer has entered the counterbore 93 which has the effect of minimizing the tendency of the displacer to 50 remain in the position shown. There is also an advantage in limiting the distance to which the displacer may enter the upper pole piece.

55 The counterbore 93 associated with the switch 94 is quite important because the gas pressure created within the displacer when the coil is de-energized adds to the effect of remanence in tending to hold the displacer at a position corresponding to that shown in Fig. 4. The counterbore 93 substantially eliminates this tendency. 60

(b) Upper pole piece

65

70 Although there is little tendency for a pull-down switch (normally called front contact switch) to fail because of remanence (this is due to the fact that the displacer is moved to the de-energized position by its own buoyancy rather than by gravity), there is nevertheless an advantage in counterboring the upper pole piece as shown at 152 in Fig. 5. In this case, the dis- 75

placer generally designated 153, is moved to the position shown in Fig. 5 by reason of the air gap 154 and when the coil 71 is de-energized, the buoyancy of the displacer returns it to its normal raised position. Details of the switch itself are unimportant here and need not be specifically described except that a time delay element 155 consisting of ceramic powder interposed between layers of cotton 156 and 157 tends to draw up a column of mercury within the displacer when the coil is de-energized, thus increasing the weight of the displacer and opposing the force of buoyancy which is acting to restore the displacer to normal position. The counterbore 152 assists the mercury in buoying up the displacer to its normal de-energized position.

(c) *Counterboring both pole pieces*

20 In some special cases, it may be desirable to counterbore both pole pieces, as shown in Fig. 6, and the switch 158 associated with the pole pieces may be either a front or a back contact switch. Some desirable effects would also be obtained by 25 counterboring the top pole piece from below rather than from above, as shown in Fig. 6.

I claim:—

1. In a mercury switch relay, a coil, an iron circuit associated with the coil including top and 30 bottom pole pieces provided with aligned apertures, a mercury switch mounted in said apertures and comprising a switch envelope, a mercury fill, spaced electrodes in the envelope, and a mercury displacer movable in response to the 35 iron circuit for changing the condition of the electrical circuit through the electrodes, and means for minimizing the effect of residual magnetism in the iron circuit, said means including a counterbore in one of the pole pieces.

2. In a mercury switch relay, a coil, an iron circuit associated with the coil including top and bottom pole pieces provided with aligned apertures, a mercury switch mounted in said apertures and comprising a switch envelope, a mercury fill, spaced electrodes in the envelope, and a mercury displacer movable in response to the iron circuit for changing the condition of the electrical circuit through the electrodes, and means for minimizing the effect of residual magnetism in the iron circuit, said means including a counterbore in the lower pole piece.

3. In a mercury switch relay, a coil, an iron circuit associated with the coil including top and bottom pole pieces provided with aligned apertures, a mercury switch mounted in said apertures and comprising a switch envelope, a mercury fill, spaced electrodes in the envelope, and a mercury displacer movable in response to the iron circuit for changing the condition of the electrical circuit through the electrodes, said lower pole piece being counterbored from the bottom to an extent that the lower portion of the displacer enters the counterbore before the upper end leaves the upper pole piece when the displacer is descending.

4. In a mercury switch relay, a coil, an iron circuit associated with the coil including top and bottom pole pieces provided with aligned apertures, a mercury switch mounted in said apertures and comprising a switch envelope, a mercury fill, spaced electrodes in the envelope, and a mercury displacer movable in response to the iron circuit for changing the condition of the electrical circuit through the electrodes, and means for minimizing the effect of residual magnetism in the iron circuit, said means including a counterbore in the upper pole piece.

5. In a mercury switch relay, a coil, an iron circuit associated with the coil including top and bottom pole pieces provided with aligned apertures, a mercury switch mounted in said apertures and comprising a switch envelope, a mercury fill, spaced electrodes in the envelope, and a mercury displacer movable in response to the iron circuit for changing the condition of the electrical circuit through the electrodes, said upper pole piece being counterbored from above for a substantial portion of its thickness.

6. In a mercury switch relay, a coil, an iron circuit associated with the coil including top and bottom pole pieces provided with aligned apertures, a mercury switch mounted in said apertures and comprising a switch envelope, a mercury fill, spaced electrodes in the envelope, and a mercury displacer movable in response to the iron circuit for changing the condition of the electrical circuit through the electrodes, and means for minimizing the effect of residual magnetism in the iron circuit, said means including the counterboring of the top and bottom pole pieces for a substantial portion of their thickness.

CARL H. LARSON.
